CLAIM

The ornamental design for a tire for automobile, as shown and described.

DESCRIPTION

1. Tire for automobile

1.1 : Front

1.2 : Enlarged

1.3 : Enlarged

1.4 : End face view

1.5 : Referential perspective view

1.6 : Back

1.7 : Top

1.8 : Bottom

1.9 : Right

1.10 : Left

The broken lines shown in the drawings represent portions of a tire for automobile that form no part of the claimed design; the long dashed and short dashed line indicates only a boundary between the portion sought to receive design registration as a partial design and the other portions; fig. 1.1 is a front elevation view of the tire for automobile showing our new design; fig. 1.2 is a partial enlarged view of A-B portion of fig. 1.1; fig. 1.3 is a partial enlarged view of C-D portion of fig. 1.2; fig. 1.4 is an end face view taken along line E-E of fig. 1.3; fig. 1.5 is a referential perspective view; fig. 1.6 is a back elevation view thereof; fig. 1.7 is a top plan view thereof; fig. 1.8 is a bottom plan view thereof; fig. 1.9 is a right side elevation view thereof; and fig. 1.10 is a left side elevation view thereof.
